UNITED STATES PATENT OFFICE.

HANS PETERSEN, OF DAVENPORT, IOWA, ASSIGNOR TO THE LINOGRAPH COMPANY, OF DAVENPORT, IOWA, A CORPORATION.

MOLD.

1,342,595.

Specification of Letters Patent.

Patented June 8, 1920.

Application filed September 9, 1916. Serial No. 119,226.

To all whom it may concern:

Be it known that I, HANS PETERSEN, a citizen of the United States, residing at Davenport, in the county of Scott and State 5 of Iowa, have invented certain new and useful Improvements in Molds, of which the following is a specification.

The invention relates to improvements in molds for casting linotypes or slugs.

10 The invention more particularly relates to that class of devices in which a series of recessed matrices impressed with the letters of the alphabet or other printing characters are assembled side by side so as to 15 form a line and positioned in front of an open ended mold cavity having its rear portion in alinement with the discharge mouth of a crucible. In carrying out the invention the matrices are provided with 20 relatively deep recesses as distinguished from shallow recesses which have heretofore been used, and when the molten metal is ejected from the crucible the same fills the mold cavity as well as the deep recesses 25 in the matrices and is then allowed to harden to produce a slug in which the overhang or character carrying portion is of a substantial width and very strong.

It is a further object of the invention to 30 provide an apparatus for casting slugs of this style in which the relatively wide overhanging portions carrying the printing characters are of sufficient strength to withstand all strain placed thereon without the 35 use of auxiliary supporting blanks or the like and to further provide a structure in which the various mold elements including the matrices may be used for casting various sized type without an adjustment of the 40 mold parts, it being understood that the slug after leaving the mold is then trimmed to any desired size by a trimming mechanism of any conventional type.

More specifically the invention comprehends the provision of a casting mold having arranged in one part thereof deep grooves for casting spacing ribs upon the body of the slug of a width equal to or greater than the overhang which is cast 50 within the recesses in the matrices. The mold also contains additional grooves or channels at its outer portion receiving the molten metal fed thereto and forming webs on the slug beneath the overhanging portion thereof extending outwardly to a point

short of the outer edge of the overhang and forming a rigid support for the overhang of the slug.

A further object of the invention is to provide the mold with a lining plate at its 60 rear end adapted to cover the grooves in one portion thereof receiving the molten metal forming the ribs on the shank of the slug and serving to terminate the channels abruptly short of the end of the mold so 65 that the ribs will terminate short of the bottom of the slug, and when the slug is passed between the pair of trimming knives no projections or fins extend beyond the rear edge thereof to cause an uneven seating of the slugs. The use of the lining plate in connection with the mold also permits the crucible to have a relatively narrow mouth piece, and it is particularly desirable when casting a slug that the mouth 70 piece be narrow in view of the fact that hardening or congealing of the molten metal from the previous cast will not very likely occur, and manifestly, if this metal should congeal during contact with the 75 conducting parts, the operation of the device would be seriously hampered.

In the accompanying drawings I have illustrated the preferred embodiment of my invention, but it will be understood that 85 many changes can be made without departing from the spirit thereof.

In the drawings,

Figure 1 is a sectional view illustrating 90 my invention.

Fig. 2 is a section on line 2—2 of Fig. 1 looking in the direction of the arrows.

Figs. 3 and 4 are detail sectional views.

Fig. 5 is a sectional view similar to Fig. 2 but of a modification.

Figs. 6 and 7 are details of the slug; and

Figs. 8 and 9 are detail views of a modified form.

Referring now more particularly to the 100 drawings wherein like reference characters indicate corresponding parts, the numeral 1 designates the throat of the crucible which is broken away for the purpose of illustration and has a relatively narrow mouthpiece 105 2, at its outer end in alinement with the mold cavity 3, the construction of the mold and the formation of the cavity will be more fully described. Positioned in advance of the mouthpiece 2 is a mold carrier 4 of any 110

approved type having an opening intermediate its ends, the walls of which support the mold, consisting of a lower body part 5, fastened to the carrier by cross bolts 5', while the upper or mold cap portion 7 is secured in position to the body in any desired manner, preferably by fastening bolts. The body portion of the mold is spaced from the cap a substantial distance to provide the mold cavity 3 for the reception of the molten metal ejected from the crucible, which metal when the same becomes hardened within the cavity forms the shank of the slug.

15 Alined against the forward end of the mold by means of interfitting tongue portions 8 or any other convenient means are the recessed matrices 9, having cutout portions 10, therein casting the overhang of the slug, 20 the recesses also being impressed with letters of the alphabet or other characters forming the printing type of the slug. It will be seen that the cutout portions of the matrices may be of any width desired and project at 25 right angles a substantial distance beyond the mold cavity receiving the molten metal from the crucible, and as the metal is passed into the mold cavity the same passes on to the recesses in the matrices, so that when 30 the metal has become hardened, a slug 12' is produced which will be of the overhang type with the overhang supported by ribs cast on the slug. It is particularly desirable to recess the matrices instead of recessing 35 the outer portions of the mold in view of the fact that the same mold may be used for casting a variety of sized type provided. The slug is cast with ribs strong enough and frequent enough to support the overhang or 40 character carrying portion sufficiently to withstand the printing pressure to which they are subjected.

It has long been the custom when using slugs of the overhanging style to place a 45 blank adjacent the shank of the slug to provide suitable supporting means for the overhanging character carrying part thereof. This has been one of the main objections to this type of slug and to the end 50 that the overhanging portion thereof be rigidly supported without the use of auxiliary supporting blanks, the mold cap has arranged therein a plurality of deep grooves 11 of a width greater than or 55 equal to the width of the recesses in the matrices for casting spacing ribs upon the shank of the slug which is cast within the mold cavity 3 and is also provided with grooves for casting supporting ribs of less 60 width than the spacing ribs, it being understood that the slugs after passing from the mold are trimmed down to the desired size by the trimming mechanism 11', which may be of any suitable type. If the supporting 65 ribs are the same height as the spacing ribs

it will not be possible to obtain so much variation in the size of the slugs by simply trimming, on account of the greater resistance to the trimming than will be the case if only the spacing ribs are trimmed. The 70 cavities 12 in the mold are spaced at regular intervals and are of substantially triangular formation, receiving a molten metal when the same is ejected from the crucible and forming on the slug a plurality of relatively 75 small supporting webs 12 which directly underlie the overhang. The cavities 12 merge with the mold cavity 3 and may be of any formation desired capable of producing the shank of the slug.

80 The spacing as well as the supporting ribs are spaced at regular intervals, and are, in actual practice spaced accordingly to standard printer's measure of one em or one-half em pitch, and the liner terminates 85 between the grooves as is the usual practice, permitting a flat liner to be used in adjusting the length of the mold cavity. When a series of molds are used with body cavities of the same dimensions with grooves for 90 casting ribs of varying height the same series of liners may be used in all the molds. On the contrary, if a continuous recess in the mold is used, as is the practice at the present time, the recess must be of different 95 width in a series of molds for casting different sizes of slugs, and liners are not interchangeable in the different molds, nor can a flat liner be used at all.

Attached to the inner face of the mold cap 100 7 and projecting a slight distance within the cavity 3, or flush with the edge of mold cavity is a lining plate 13 which prevents the forming of the spacing ribs upon the base of the slug, as this plate closes the channels 105 11 within the mold cap abruptly short of the bottom, and therefore, when the slug has been passed between the trimming knives if any projecting fins should be forced toward its bottom the same would not extend a sufficient distance so as to cause an uneven seating of the slug when the same is assembled with other slugs. While I preferably use the lining plate for this purpose it will be clearly understood that any suitable means 110 for accomplishing this end can be used without departing from the invention. The use of the lining plate 13 also permits the utilizing of the relatively narrow mouthpiece 2, and this is particularly desirable in view of 115 the fact that it is necessary to keep the type metal of such a temperature that it will not become solid in the sprue holes of the mouthpiece when the metal forming the slug is separated therefrom, so that small particles 120 of metal will not adhere or harden on the mouthpiece because the surfaces of the mouthpiece coming in contact with the mold are comparatively small and narrow.

125 In Fig. 6 I have illustrated several forms 130

of slugs that can be cast within the mold embodying my invention, it being noted that the slugs may be cast with both the spacing ribs and supporting webs thereon or only 5 the spacing ribs.

While I have described and illustrated the preferred embodiment of my invention it will of course be understood that many 10 changes in size, arrangement and combination of parts may be made without departing from the spirit of the appended claims.

Having thus described the invention what I claim is:

1. A linotype mold having a cavity to 15 form the body of a slug, and said mold being provided with grooves for forming spacing ribs on the body of the slug and also with grooves for forming character supporting ribs on the body of the slug of less height 20 than the spacing ribs.

2. A linotype mold for producing a slug with a character-carrying overhanging portion, said mold being also provided with grooves for forming spacing ribs on the 25 slug, and also with grooves of less depth than the first mentioned grooves for forming supporting ribs for said overhanging portion.

3. A linotype mold having a cavity to 30 form the body of a slug, and said mold being provided with relatively deep grooves for forming spacing ribs on the slug, and also with grooves therein at one side thereof of less depth and of less length than the first

mentioned grooves for forming character 35 supporting ribs on the slug.

4. A slug of the character described having a body portion and an overhanging portion at one side thereof, relatively short supporting ribs for said overhanging portion 40 extending from the body at one side of the overhanging portion of the slug, said supporting ribs being of less height than the height of said overhanging portion of the slug, and a plurality of spacing ribs on the 45 body portion of greater height than said overhanging portion of the slug.

5. In an apparatus of the character described the combination with matrices provided with recesses to form an overhanging 50 portion of a slug, of a mold having a cavity of less depth than the depth of the recesses in the matrices to form the body of a slug, the mold being also provided with grooves for forming supporting ribs for the overhanging 55 portion of the slug of a height less than the height of said overhanging portion, and the mold also having grooves of greater depth than the first mentioned grooves for forming spacing ribs on the slug 60 of a height greater than the overhanging portion of the slug.

In testimony whereof I affix my signature in the presence of two witnesses.

HANS PETERSEN.
